United States Patent Office

Des. 183,800
Patented Oct. 28, 1958

183,800

SUCTION CLEANER

Raoul A. Lambert, Ludlow, Mass., assignor to Westinghouse Electric Corporation, a corporation of Pennsylvania

Application December 10, 1957, Serial No. 48,855

Term of patent 14 years

(Cl. D9—2)

FIG.1.

FIG.2.

Fig. 1 is a front perspective view of a suction cleaner embodying my new design; and

Fig. 2 is a rear perspective view of the suction cleaner of Fig. 1.

I claim:

The ornamental design for a suction cleaner, substantially as shown.
